UNITED STATES PATENT OFFICE.

JUDSON PRICE, OF POPLAR BLUFF, MISSOURI.

SEWER-CLEANING MEANS.

1,215,189.

Specification of Letters Patent.

Patented Feb. 6, 1917.

Application filed May 18, 1916. Serial No. 98,328.

To all whom it may concern:

Be it known that I, JUDSON PRICE, residing at Poplar Bluff, in the county of Butler and State of Missouri, have invented a new 5 and Improved Sewer-Cleaning Means, of which the following is a specification.

My invention is an improved means for 10 cleaning the off-take pipes for street sewers, toilet stools, wash basins, bath tubs and sinks, by flushing same with water taken 15 from a street supply or the flush box for basins, tubs, etc., and primarily my invention has for its purpose to provide a simple and inexpensive coöperative arrangement of parts which constitute my said 20 sewer pipe cleaning means that can be readily made up to satisfy the special character of sewer pipes to be cleaned.

With other objects in view that will hereinafter appear, my invention consists in the peculiar construction and novel arrangement 25 of the parts to be first described in detail, specifically pointed out in the appended claims and illustrated in the accompanying drawing, in which:

Figure 1 is a vertical section, parts being in elevation, of my sewer cleaning means, the parts being particularly designed for flushing or cleaning the off-take of a street 30 corner sewer or sink.

Fig. 2 is a top plan view thereof.

Fig. 3 is a side elevation of my sewer cleaning means and illustrates its use in connection with toilets and overhead flushing 35 tanks.

Fig. 4 is a similar view that shows my invention as applied to a toilet or sink.

Fig. 5 is a detail section of the plug device 40 for making the air tight connection for the improved cleaning means, and

Fig. 6 is a detail cross section of the inflatable gasket that forms a part of the closure device.

In the drawing I have shown my invention 45 as designed for cleaning the off-take or sewer pipe from a street corner basin or sink, it being understood that the same generic coöperative arrangement of the parts that is shown in Fig. 1 may be readily 50 modified for use in connection with toilet bowls, kitchen sinks, as will be hereinafter further described, and without departing from the generic features of my invention, as is set out in the appended claims.

My invention embodies a main flushing 55 pipe or tubular section 1, one end of which is externally threaded for receiving the screw cap end 20 of a hose connection 2, which, when cleaning sewers for corner sinks, as shown in Fig. 1, is connected with 60 the street water supply but when my invention is utilized for cleaning toilets, bath tubs, &c., the said hose connection is joined with the overhead flush box, as is indicated in Fig. 3.

3 designates a tubular leg that is joined 65 with one end of the main pipe 1 and is projected at right angles thereto. The upper end of the said leg has an elbow joint 30 that connects with the main pipe and the lower end has an elbow joint 31 provided with a seat 32, the reason for which will presently appear.

As is clearly shown in Fig. 1, a nozzle or discharging end 33 projects from the elbow 75 31 and extends horizontally at right angles to the leg member 3 and when operatively applied, it passes into the open end of the sewer pipe 8, as shown.

6 designates a closure disk or plate which 80 is of sufficient diameter to snugly seat on the internal annular shoulder 80 formed on the end of the sewer pipe 8 that is attached to the well of the sewer, as shown.

Plate 6 is removably mounted on the 85 threaded end of the nozzle member 33 and it has an annular flange 60 that is suitably spaced from the outer edge of the rim to leave an intervening space between the wall of the pipe shoulder 7 and the said flange 90 60, the purpose for which will presently appear.

11 designates a pneumatic gasket that surrounds the flange 60 and the gasket may be formed similar to an ordinary pneumatic 95 tire tube but it is preferably formed of an inner inflatable tube 11^a and an outer pliable canvas casing 11^b.

The gasket 11 has the usual valve air inlet 12 that joins with one end of a hose connection that connects with an air pump 13 suitably mounted on a bracket 14, clamped or otherwise secured to the main pipe 1.

15 designates a force pump that is also suitably mounted on the bracket 14 and 105 which includes a pipe section 16 that is in communication with the main pipe 1 at the rear of a gate valve 17 located in the said

pipe 1, and a pipe section 18 which is in communication with the pipe 1 at a point in advance of the gate valve, as shown.

In the practical application of my cleaning means, when applied to a street corner sewer trap, as shown in Fig. 1, the main pipe 1 with its attached parts is located on the pavement adjacent the manhole of the sewer with the leg portion 3 held pendent in the trap and the nozzle member that carries the plug disk 6 projected toward the flange mouth of the off-take or sewer pipe 8.

The leg 3 and nozzle 32 are then pulled over to project the nozzle 32 into the said pipe 8 until the plug disk 6 seats in the flange bearing that surrounds the mouth of the pipe 8.

When thus positioned, the disk 6 is firmly seated, air tight, over the said mouth of the sewer pipe by means of a brace jack that consists of a lever 19 which extends up to near the top of the manhole, a slotted socket and a ratchet bar 21, one end of which engages the seat 32 in the elbow 31, as is clearly shown in Fig. 1.

After the parts are assembled as stated, a positive air tight closure for the disk 6 on the outer end of the sewer pipe, is effected by inflating the tubular gasket 11, which is done by operating the air pump carried upon the main pipe 1, as shown.

When thus applied, the gate valve 17 is opened and the hose street connection is turned on to allow the flushing water, under the normal pressure, to pass straight through the pipe 1 and eject from the nozzle end 33, against the obstructions in the sewer pipe.

In case the normal water pressure from the hose connection is not sufficient to clear the sewer pipe, and that is usually the case, when using the overhead flushing tank for toilets, &c., the gate valve is closed and the force pump is then brought into action which takes the flushing water, that enters the pipe 1, back of the gate valve, and delivers it, under forced pressure, back into the said pipe 1 at a point in front of the said gate valve.

It is to be understood that while in Fig. 1 I have shown a ratchet lever and rack form of brace jack for holding the closure disk 6 in tight connection with the mouth of the sewer pipe, the said means may be modified to suit the special application of my sewer cleaning means. For example, when using the same for flushing toilet bowls, as seen in Fig. 3, a special form of gasket 11 is provided to suit the shape of the bowl and a yoke clamp 40 is used for holding the parts to their operative condition. When applied to the toilet bowl, as in Fig. 3, the flushing pipe is extended up over and into the overhead flush tank.

Fig. 4 shows my invention adapted for flushing the sewer pipe or trap for kitchen

sinks. When thus utilized, the nozzle end of the main pipe is externally threaded as at 35 to receive a screw nut 36 that carries a pendent wedge collar 37 for engaging and spreading a rubber plug 38, to cause the said plug to fit air tight in the basin outlet 39.

When used for cleaning the sewer trap for sinks, as shown, the sink is kept filled with water from the supply tap and the flushing hose is extended into the water and during the operation of cleaning the sink outflow pipe, the overflow or vent for the sink is closed by a rubber pad α , as shown.

In case there be more than one opening in the sewer trap during the application of my invention, another of my improved outfitts could be used for taking care of such other opening.

From the foregoing taken in connection with the drawing, the complete construction, the manner of operation and the advantages of my invention will be readily apparent.

The said means can be compactly assembled, easily applied for use and when operatively adjusted, effectively serve to disturb any collected matter within the sewer pipe and carry the same outward with the flushing water.

What I claim is:

1. A sewer cleaning means comprising a nozzle adapted to be inserted into the duct to be flushed, a member on the nozzle for closing the end of the duct that surrounds the nozzle and for holding the nozzle from being forced downward into the duct, means for forcibly holding the closure member on the nozzle seated over the duct and other means for effecting a fluid tight sealing of the said closure member over the duct, and further means for forcing fluid through the nozzle into the duct, the said first named means consisting of a brace jack adapted to engage a part of the casing surrounding the duct to be flushed, and the nozzle. 110

2. A sewer cleaning means comprising a nozzle member adapted to be inserted into the duct to be flushed, means for sealing the said member in the duct, means for holding the said member in the duct and means for forcing fluid through the nozzle into the duct, said means including a main pipe in connection with the nozzle and with the fluid supply, a gate valve in the main pipe, a force pump having laterals, one of which communicates with the main pipe at the rear of the gate valve and the other of which communicates with the said pipe in front of the gate valve, each of the said laterals including a back check valve. 120

3. In a sewer cleaning means of the character described; the combination with a fluid injecting pipe, a nozzle attached thereto and means for holding the said nozzle fluid tight and extended into the duct to be 130

flushed, the said fluid injecting pipe including a main or body portion; of a gate valve located in the said main pipe, a force pump, means for attaching the said pump to the main pipe, the said pump including valved laterals, one of which discharges into the main pipe in advance of and the other of

which discharges into the main pipe to the rear of the gate valve.

JUDSON PRICE.
